A. W. KIRTON

SPRAY HEAD

Filed Oct. 11, 1922

UNITED STATES PATENT OFFICE.

ARTHUR W. KIRTON, OF PHILADELPHIA, PENNSYLVANIA.

SPRAY HEAD.

Application filed October 11, 1922. Serial No. 593,747.

To all whom it may concern:

Be it known that I, ARTHUR W. KIRTON, a citizen of Great Britain, and a resident of Philadelphia, in the county of Philadelphia and State of Pennsylvania, have invented a new and useful Improvement in Spray Heads, of which the following is a specification.

My invention relates to spray heads, particularly adapted for use in washing machines of the spray type and has for its object to provide apparatus of the character designated which shall be highly effective in the production of a washing spray, and which may be readily cleansed as is desirable in apparatus of this character.

In the accompanying drawing, Fig. 1 is a side view, partially in section and partially in elevation, of a spray head embodying a preferred form of my invention; Fig. 2 is a top plan view of the apparatus shown in Fig. 1; and Fig. 3 is an end view of the apparatus shown in Fig. 1, partially in section and partially in elevation.

In a copending application of Henry F. Schmidt, Serial No. 593,724 filed October 11, 1922, there is described and claimed a dish washing machine embodying means for maintaining two or more horizontally disposed tiers of dishes, vertically displaced from each other and with means for providing a whirling spray therebetween.

The present invention relates to a specific form of spray head which is highly effective when used in such a machine.

Referring to the drawing, I show at 5 an upstanding fluid supply pipe terminated in an open upper end.

A T-shaped member 6 is provided with a hollow stem 7 adapted to telescope over the end of the pipe 5 and also carries a weight member 8, symmetrically disposed with respect thereto.

The head portion of the T-shaped member 6 is in the form of a substantially semi-circular trough, opening upward, as clearly shown in Fig. 3 and the two ends of this trough-shaped portion are closed by substantially quarter-spherical portions 9 and 10, so terminating that the plan view of the upper face of the trough is as shown in Fig. 2, being in form of a rectangle with circular ends. One side of one end of the head member is perforated, as shown at 11, and the other side of the other end is similarly perforated (not shown). The trough-shaped

head is closed by a cover member 12 in sliding engagement therewith, this cover member being of the shape shown in Fig. 2 and having lateral depending flanges 13 and 14 for engagement with suitable flanges on the straight edges of the trough-shaped member. The cover member 12 embodies semi-circular extensions at the end thereof for the complete closure of the trough-shaped member. The cover member 12 is suitably perforated as shown at 15 for the emission of upwardly directed sprays.

A flow directing member 16 is mounted within the trough-shaped top of the member 6 and is of such contour that a circular stream of fluid rising from the pipe 5 is split into two semi-circular streams of fluid, directed into the respective ends of the head of the member 6. The member 16 is suitably supported from the side walls of the member 6 and is merely in contacting engagement with the cover member 12.

Having thus described the structure of apparatus embodying my invention, the operation thereof is as follows: Upon the supply of fluid through the tube 5 to the head 6, downwardly directed sprays are produced at the perforations 11—11 and upwardly directed sprays are produced at the perforations 15—15. The fact that a preponderance of the sprays on one end of the head member are on one side thereof, and a preponderance of the perforations of the other end of the head are on the opposite side thereof, causes an unbalanced reaction tending to rotate the entire member 6 about the axis of the member 5, thus providing the desired whirling spray action.

While I have shown all of the perforations in one end of the head member as located on one side thereof, it will be obvious that a certain number of perforations may be placed on the other side thereof, the main requisite being that there be a preponderance on one side so as to cause the unbalanced rotating action.

The action of the member 16 is to cause a smooth, uniform, diverging direction of the incoming stream to the respective perforations and the weight 8 prevents the pressure of the incoming fluid from blowing the head structure from the pipe 5.

When the necessity arises for cleaning the device, the entire head member may be lifted bodily from the pipe 5 and removed from the machine, and the cover member 12 may

then be slid therefrom, exposing the entire interior of the spray head for such cleansing as may be necessary.

While I have shown but two radiating arms, it is obvious that I may employ a greater number of radiating arms with suitably adapted removable covers therefor.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. A spray head comprising a revolvably mounted member embodying a plurality of substantially horizontally disposed, hollow, open-topped radiating arms, a removable cover member thereover, said cover member being perforated, and means for supplying fluid to the interior of said head.

2. A spray head comprising a revolvably mounted member embodying a plurality of substantially horizontally disposed, hollow, open-topped radiating arms provided with perforations therethrough, a preponderance of said perforations facing in the same rotative direction, whereby the emission of sprays therefrom establishes an unbalanced reaction tending to turn said head, and a removable cover member for said members.

3. A spray head comprising a revolvably mounted member embodying a plurality of substantially horizontally disposed, hollow, open-topped radiating arms provided with perforations therethrough, a preponderance of said perforations facing in the same rotative direction, whereby the emission of sprays therefrom establishes an unbalanced reaction tending to turn said head, and a removable perforated cover member for said members.

4. A spray head comprising a perforated trough-shaped member of substantially semi-circular cross-section, having closed ends, mounting means therefor permitting rotation thereof about a transverse axis normal to the facial plane, removable means for closing the open face thereof, and means for supplying fluid thereto.

5. A spray head comprising a perforated trough-shaped member of substantially semi-circular cross-section, having closed ends, mounting means therefor permitting rotation thereof about a transverse axis normal to the facial plane, removable perforated means for closing the open face thereof, and means for supplying fluid thereto.

6. A spray head comprising a perforated trough-shaped member of substantially semi-circular cross-section, having closed ends,

mounting means therefor permitting rotation thereof about a transverse axis normal to the facial plane, a preponderance of the perforations therein facing in the same rotative direction, whereby the emission of sprays therefrom tends to cause rotation of said head, removable means for closing the open face thereof, and means for supplying fluid thereto.

7. A spray head comprising a hollow T-shaped member, the stem thereof being of circular cross-section and adapted to telescope over the open end of a supply pipe, the head thereof being open at the top and of substantially semi-circular cross-section with closed ends and provided with spraying perforations, and a sliding cover member over the open face of said head member.

8. A spray head comprising a hollow T-shaped member, the stem thereof being of circular cross-section and adapted to telescope over the open end of a supply pipe, the head thereof being open at the top and of substantially semi-circular cross-section with closed ends and provided with spraying perforations, and a sliding perforated cover member over the open face of said head member.

9. A spray head comprising a hollow T-shaped member, the stem thereof being of circular cross-section and adapted to telescope over the open end of a supply pipe, the head thereof being open at the top and of substantially semi-circular cross-section with closed ends provided with spraying perforations, a preponderance of said perforations facing in the same rotative direction with respect to rotation about the axis determined by said telescope joint, and a sliding cover member over the open face of said head member.

10. A spray head comprising a hollow T-shaped member, the stem thereof being of circular cross-section and adapted to telescope over the open end of a supply pipe, the head thereof being open at the top and of substantially semi-circular cross-section with closed ends and provided with spraying perforations, a preponderance of said perforations facing in the same rotative direction with respect to rotation about the axis determined by said telescope joint, and a sliding perforated cover member over the open face of said head member.

11. A spray head comprising a hollow T-shaped member, the stem thereof being of circular cross-section and adapted to telescope over the open end of a supply pipe, the head thereof being open at the top and of substantially semi-circular cross-section with ends of quarter-spherical contour and provided with spraying perforations, and a sliding cover member over the open face of said head member.

12. A spray head comprising a hollow

- T-shaped member, the stem thereof being of circular cross-section and adapted to telescope over the open end of a supply pipe, the head thereof being open at the top and 5 of substantially semi-circular cross-section with closed ends and provided with spraying perforations, a sliding cover member over the open face of said head member, and a flow-line filler of such contour opposite the 10 end of said stem that an incoming stream of substantially circular cross-section is divided thereby into two streams of substantially semi-circular cross-section for supply to the two ends of said head.
15. 13. A spray head comprising a hollow T-shaped member, the stem thereof being of substantially circular cross-section and

adapted to telescope over the open end of a supply pipe, the head thereof being of substantially semi-circular cross-section with 20 closed ends and with spraying perforations therethrough, a cover member for the flat face of said head member, and a flow-directing member having concave faces disposed in said head above said stem for splitting the flow of fluid through said stem into two streams of semi-circular cross-section and for directing said streams into the respective portions of said head member.

In testimony whereof, I have hereunto 25 subscribed my name this 6th day of October, 1922.

ARTHUR W. KIRTON.
